D. D. GOOD.
AUTOMATIC TRAIN STOPPING DEVICE.
APPLICATION FILED OCT. 14, 1915.

1,294,651.

Patented Feb. 18, 1919.

WITNESSES:

David B. Good.

ATTORNEY.

UNITED STATES PATENT OFFICE.

DAVID D. GOOD, OF PHILADELPHIA, PENNSYLVANIA.

AUTOMATIC TRAIN-STOPPING DEVICE.

1,294,651.

Specification of Letters Patent. Patented Feb. 18, 1919.

Application filed October 14, 1915. Serial No. 55,830.

To all whom it may concern:

Be it known that I, DAVID D. GOOD, a citizen of the United States, residing at 6203^B Jefferson street, Philadelphia, and 5 State of Pennsylvania, have invented a new and useful Improvement in Automatic Train-Stopping Devices.

My invention relates primarily to the provision of safety air ports in the essential 10 parts of a train, or other vehicle equipped with air brakes, which will stop the train if any essential part is broken or fractured.

The drawing and specification show how my invention may be applied to stop levers 15 and control levers of automatic train stopping devices such as are described in my applications for Letters Patent #4,945, automatic speed control, filed January 28th, 1915, and #835,652, automatic train stopping device, filed May 1st, 1914, and to other essential parts of a train, such as the wheels, 20 axles, etc.

Throughout the accompanying drawing similar letters and figures refer to similar 25 parts. On inspection of the above mentioned applications it will be seen that the numeral references herein refer to similar parts illustrated in those applications and that the letters refer to the new matter constituting my improvement.

Figure 1 is a broken vertical elevation and section of a part of an automatic speed control with my improvement added thereto.

Fig. 2 is a horizontal sectional view of 35 control lever on the line Y X, Fig. 1.

Fig. 3 is a plane side elevation of a shoe carried by a train.

Fig. 4 is a horizontal cross section on the line V W, Fig. 3, through the stem of the 40 shoe.

Fig. 5 is a vertical cross section through the base of the shoe on the line O P.

Fig. 6 is a broken rear elevation and section through the knuckle joint of the shoe 45 and on a perpendicular plane to that of Fig. 3.

The valve block 1, the webs 5, 6 and 7 and the table 8 form part of the framework of a speed controlling device attached 50 to a vehicle equipped with air brakes.

The stop lever 13 is designed to be turned by a tripping device placed adjacent to the track. The circular members 18 and 20, which are permanently attached to the stop 55 lever, turn in bearings in the webs 6 and 7.

When the stop lever is turned on its pivot thus formed, the cams 11', which are similar to the cams 11 shown in Fig. 2, operate to open a valve in the port 77 which is connected to the brake line and thus bring the 60 train to a full stop.

The control lever 10 slides vertically on the pivot 21 and operates a valve in the port 78 in a similar manner. These valves and their operation are not shown or described as they have no direct relation to the improvement now to be discussed.

The port 78 may be any port in a valve block leading directly to the air brake line of a vehicle or train. Connected with and 70 leading from the port 78, a port e leads downward through the valve block 1; from thence a port f leads outward through the web 5 and around the bearing in which the circular member 22 of the pivot 21 turns. 75 The end of this port is closed, forming in effect a hollow web with its only outlet at 5'. The outlet 5' is provided with a connection for a flexible hose g. The opposite end of the hose g is connected at h' with 80 the control lever 10. The control lever 10 is of hollow construction or provided with ports h and h'. The said hollow portion or ports are connected to or open into the flexible hose g. It will be seen that, as these 85 airways have no opening, so long as the parts remain intact, the compressed air in the air brake line will not be allowed to escape through them but that immediately on their being fractured or broken, through 90 any cause whatever, the air under compression in the air brake line of the vehicle, will escape and set the brakes in the usual manner.

The same result is obtained by a similar 95 construction of the stop lever 13. From a port 78 in the valve block 1, the port a leads upward to the port b which leads outward through the web 6 to the conically ground seat. A conical member 20 attached to or 100 forming a part of the stop lever 13 turns in this seat and is provided with a groove c' around its face. Ports c extend from the groove c' to the center of the member under discussion and upward to a meeting 105 with the longitudinal port d in the stop lever 13.

A circular member 18, which is formed on the stop lever 13, turns in an opening in the web 7. On the web 7 an internally threaded 110

collar 7' is formed. Into this collar, an externally threaded hollow nut is screwed which bears on the upper edge of the member 18 and forces the conical member 20 to 5 an air tight seat.

This construction allows the air pressure in the hollow stop lever 13 to equal that in the air brake line of the vehicle at all times regardless of the direction in which the handle is turned. If the stop lever should be 10 broken by contact with a tripping device or any other object, the air from the brake line would escape through the fracture and set the brakes on the vehicle.

15 A shoe, on a vehicle or train, for the operation of signals or automatic tripping devices and which is an essential part of my invention may be provided with my improvement. As it is sometimes desirable that such 20 shoes have a knuckle joint in order that they may turn forward and upward when the vehicle backs past a signal or trip, I have illustrated one of this character in Figs. 3, 4, 5 and 6.

25 A block 3, attachable to a vehicle by the eyes *i*, has a threaded pipe connection *j* attached to it. This connection provides means of connecting the horizontal port *k* in the block with the air brake line of the 30 vehicle.

35 A conical projection *l*, fixed to the block 3, forms a pivot which is ground to fit a conical opening in the sleeve *o*. A port extends outward from the port *k* through the conical projection *l* and connects with the vertical port *m*. The latter terminates in a groove *n*, cut around the cone *l*. The sleeve *o* is held in place by the nut *y* which screws on a threaded extension on the cone *l*.

40 Attached to the sleeve *o* is a stem, formed of the perpendicular webs *p* and *q*. The web *q* extends down to and is attached to the base 2 of the shoe. The web *p* is ex-

tended longitudinally to form the webs *v* and *w* and strengthen the base 2.

The lug *x* is attached to the block 3, extends outward beyond the inside edge of the web *q* and prevents the shoe from turning backward beyond the vertical.

45 A groove *n* extends around the inside of the sleeve *o* and registers with the groove on the cone *l*. From the groove *n*, an air port *s* extends downward through the center of the stem and connects with the longitudinal ports *t* and *u*.

50 When the construction necessitates the drilling of the ports or leaving sand openings in casting, the ends of the ports are closed by screw plugs *z*.

55 By the construction of a shoe with the safety ports as described, it will be seen that, should the shoe be broken or torn loose from the vehicle in such a way that it might fail to operate signals or tripping devices, a direct opening would be made through to the air brake line and allow the air under compression therein to escape into the atmosphere and set the air brakes.

60 Having thus described my invention, I claim as novel:

65 In an automatic train stopping device, the combination with the air brake line, and a valve block connected thereto, of a port or air way extending from the air brake line through said valve block, a hose connection, a vertically sliding control lever of hollow 70 design and a flexible hose or tube adapted to connect the two and form a continuous air way from the air brake line to the hollow lever and allow the latter to move on its 75 pivot, substantially as described.

80 DAVID D. GOOD.
